UNITED STATES PATENT OFFICE

ELMER L. OGLE, OF AURORA, ILLINOIS, ASSIGNOR TO ALL-STEEL-EQUIP COMPANY, OF AURORA, ILLINOIS, A CORPORATION OF ILLINOIS

SWITCH PANEL

Application filed September 10, 1927. Serial No. 218,794.

The invention relates to electrical panel boards, and more particularly to the mounting of switch units therein.

One of the objects of the invention is the provision of a panel board having new and improved means for mounting the switch units thereon, whereby the wiring may be accomplished with ease and rapidity.

Another object of the invention is the provision of a panel board having new and improved means for mounting the switch units therein, whereby they may be readily adjusted to the proper position relative to the flush plate in installing the panel board in the wall of a building.

A further object of the invention is the provision of a new and improved panel board that is cheap to manufacture, easily assembled, neat in appearance, efficient in use, one in which the parts are not likely to become deranged or get out of order, and one in which the units may be readily adjusted relatively to the face plate.

Other and further objects and advantages of the invention will appear from the following description taken in connection with the accompanying drawings, in which:

Fig. 1 is a front elevation of the panel board with parts in section and parts broken away;

Fig. 2 is a perspective view of one of the supporting bars for the switch units;

Fig. 3 is a section on line 3—3 of Fig. 1;

Fig. 4 is a section on line 4—4 of Fig. 1;

Fig. 5 is a perspective view of the fuse holder;

Fig. 6 is a front elevation of a modified form of switch panel;

Fig. 7 is a section on line 7—7 of Fig. 6, and,

Fig. 8 is a detail on line 8—8 of Fig. 6.

It is the common practice in panel boards to mount the switch unit on the flush plate and secure the plate to the cabinet or tub by screws, bolts or the like. This arrangement is objectionable because of the difficulty of wiring the units and of properly adjusting the parts. The present invention seeks to avoid these difficulties by providing means whereby the switch units may be wired and

properly adjusted in the cabinet before the finishing plate is applied.

Referring now to the drawings, in which similar characters designate the same parts throughout the several views, the reference character 8 designates generally the panel board which comprises a container or box 9 known in the art as a tub, for housing or containing the fuse sockets 10 and switch elements 11. It is the common practice to secure the tub 9 in position in the wall of the building before the plastering is applied.

The fuse sockets and switch units are secured in the container or tub in a manner that will now be described.

In the form of the device selected to illustrate one embodiment of the invention, which is, by way of example only, a group of switch elements constituting a switch unit 12, is removably mounted at each side of the box. The arrangement of the switch units is immaterial. As shown in Fig. 1 each unit comprises four switch elements 11 rigidly connected together. Each of the switch elements 11 comprises the panel supporting plate 13, on which is mounted the switch lever or button 14 and the insulating member 15 carrying the binding screws and contact members, as is usual in such constructions. The outer ends of the supporting plates 13 are detachably attached to inwardly extending flanges 16 on the angular supporting bars 17, as by means of screws 18. When the four switch elements 11 are thus rigidly attached to the supporting bars 17, the said bars and elements constitute what may be termed a switch unit, which may be removed from the box or tub as a rigid structure.

A bar 19 is provided at each side of the tub or container 9 for supporting the inner portion of the switch units. These bars and the side walls of the tub or container are provided with screws 21 and 22, which are opposite each other and are located at each end of the tub. Each of the bars 17 has its body portion 23 extending beyond the flange 16 and provided with slots 24, which are adapted to engage the screws 21 and 22 for securing the switch unit in position in the tub. By means of the slots 24 the unit may be ad-

justed inwardly or outwardly, as occasion requires.

The fuse sockets are preferably mounted on the bottom wall of the box between the switch units. Any means may be employed for attaching the fuse sockets to the bottom wall of the box. As shown they are mounted on bars 25, which have their ends offset and attached to the bottom wall of the box in any suitable manner, as by means of the screws 26. Preferably the ends of the bars 25 are provided with slots 30 extending transversely of said bars, whereby the bars may be attached to the screws by unloosening the same and moving the bars laterally to cause the slots to engage the screws beneath the heads thereof, after which the screws may be tightened for clamping the bars in position.

Each of the fuse sockets is provided on its under surface with notches, in which may be secured the busbars or electrical conductors 27. (See Fig. 3.) Each of the fuse socket members 28 is preferably provided with two sockets 29 of the usual, or any well known construction. Each fuse socket element has its outer end reduced, as at 31, to form a shoulder 32, forming an abutment for the guard 33, as will presently appear.

A suitable finishing plate is provided which constitutes a closure for the tub or container 9. As shown, a plate 34 is employed for this purpose. This plate is adapted to be held on the tub or container in any suitable manner, as by the screws 35, which extend through said plate and are threaded into plugs or tabs 36 rigidly secured in the corners of the tub or container. The plate is provided at each side thereof with openings 37, through which the switch levers or buttons 14 are adapted to extend. The plate is also provided with a central opening 38, through which access may be had to the fuse sockets. A suitable door or closure 39 is provided for said opening. The door 39 is hinged to the marginal edge of the opening, as by means of the hinges 41, and is provided on its free end with a spring latch member 42, which is adapted to engage a corresponding keeper 43 for holding the door in closed position. (See Fig. 4.)

Attached to the inner side of the door opening, and extending entirely around the same, are the angle bars 44. The flange of these bars that is attached to the plate extends inwardly beyond the edge of the opening to form an abutment for said door. The other flange is provided with a plurality of screws 45, which are adapted to engage slots 46 in the guard member 33 for holding the same in adjusted position. The guard member 33 is in the form of a rectangular box having slots extending inwardly from the outer edge thereof, whereby the guard member may be adjusted inwardly or outwardly, as occasion may demand.

The bottom wall of the guard is provided with openings which correspond to the size and shape of the reduced portion 31 of the fuse sockets 28. By loosening the screws 45 the guard 33 can be so adjusted that when the door 39 is closed, the bottom wall of the guard will rest on the shoulders 32, as clearly shown in Fig. 4 of the drawings.

In the construction of buildings the tub is attached to the wall before the plastering is applied, and after the plastering has been applied the switch elements, fuse socket members, and the finishing plate are attached. The fuse socket members which have previously been mounted on the bars 12 are attached to the bottom wall of the tub by loosening the screws 26 and moving the entire unit laterally to cause the slots 30 in the ends of the bars 25 to engage the screws beneath the heads thereof, after which the screws are tightened for clamping the bars in position. The switch units are then applied at each side of the box by unloosening the screws 21 and 22 and forcing the units inwardly, causing the slots 24 in the bars 23 to engage said screws beneath the heads thereof. A straight edge is then placed across the box and the plastering at each side thereof, after which the switch units are moved outwardly until they come in contact with this straight edge, after which the screws 21 and 22 are tightened for clamping the bars 23 in position.

The finishing plate may now be attached, and since the switch units have been brought out to the plane of the outer surface of the plastering, the switch levers or buttons 14 will extend the proper distance through the openings in the finishing plate. After the plate is attached, the guard member 33 may be adjusted to the proper position by loosening the screws 45, as previously described.

A fuse plug holder 51, having the circular openings 52 for holding extra fuse plugs, is adapted to be placed in the lower portion of the space formed by the guard 33. The holder is preferably channel shape in cross section with its inner flange 53, (see Figs. 4 and 5), longer than its outer one and with its web portion arranged at an angle inclined downwardly toward the front whereby articles cannot be left on the same when the holder is in position in the lower portion of the guard 33, as clearly shown in Fig. 4.

It will thus be seen that a switch panel has been provided in which the box or tub alone may be placed in position in a building, and that after the plastering has been applied the fuse sockets and switch elements may be mounted on supporting bars and inserted as a unit within the box and properly adjusted independently of the face or finishing plate 34. The face plate is now attached after the fuse socket and switch element units have been properly adjusted in position within the box,

thus saving time and expense in their installation.

In the modified form of construction shown in Figs. 6, 7 and 8 only one row of switch elements is disclosed, but this is immaterial. 5 This form of construction differs from that shown in Figs. 1 to 5 inclusive in that the supporting bars 54 for the switch elements 11 are loosely supported from the wall 55 of the tub or switch box 56 and the cross bars 57. 10 As shown inwardly off-set tongues 58 and 59 on said wall and cross bar, respectively, are provided for receiving the inwardly extending flanges of the angle bars 54. The laterally extending flange portions 54^a of the angle bars are provided with screw-threaded openings for receiving screws 61 which are adapted to extend through the face or finishing plate 63 for drawing said unit up against 15 said plate, whereby the switch levers 14 will be brought to the proper position.

The construction of the fuse socket unit and the manner of detachably mounting the same within the switch box is substantially 20 the same as in the previously described construction and its description need not be repeated here. The same is also true of the guard member and finishing plate.

In assembling the device shown in Figs. 20 5 to 8, the tub or box is attached to the wall before the plastering is applied, as in the previously described construction, the leads are brought into the box and the switch and fuse socket elements are wired and mounted 35 on supporting bars to form switch and fuse socket units, respectively. The fuse socket unit is attached as above. The switch unit is placed in position and the face or finishing plate 63 is applied. It is secured to the box or tub 56 by suitable fastening means, as the screws 64 extending therethrough and engaging threaded brackets or tabs 65 rigidly secured to said box. The screws 61 are next applied and by means of the same the switch 45 unit is drawn forwardly to the proper position to cause the switch levers to extend through the plate to the desired position.

It is thought from the foregoing taken in connection with the accompanying drawings that the construction and operation of my device will be apparent to those skilled in the art, and that various changes in size, shape, proportion and details of construction may be made without departing from 55 the spirit and scope of the appended claims.

I claim as my invention—

1. In a panel board, a tub, a partition within said tub, supporting bars, means for adjustably mounting said bars on said partition and tub, said means comprising fastening elements for engaging slots in said bars whereby said bars may be adjusted inwardly and outwardly within said tub, and a plurality of switch elements mounted on 60 said bars, said elements having operating

levers, and a finishing plate mounted on said tub and having openings through which said levers extend.

2. In a panel board, a container, a cross-bar within said container, screws threaded into said bar and the wall of said container and arranged in pairs opposite to each other, a pair of supporting bars having slots therein for engaging said screws, whereby said supporting bars may be adjusted toward and from the bottom of said container, and a plurality of switch elements rigidly mounted 70 75 on said supporting bars.

3. In a switch panel, a container, a cross-bar secured within said container to opposite walls thereof, screws threaded into said cross-bar and the adjacent parallel wall of said container and extending laterally therefrom, a pair of supporting bars, a plurality of switch elements rigidly mounted on said supporting bars, said supporting bars being provided with slots for adjustably engaging said screws for adjusting said elements toward and from the bottom of said container and a finishing plate extending over said container and having openings therein through which the switch levers and buttons are adapted to extend.

4. In a switch panel, a tub member, a plurality of switch elements, each element being provided with a switch lever, means for rigidly mounting said elements as a single unit, means for adjustably mounting said unit within said container within said tub, said means comprising fastening elements engaging slots in said unit, whereby said unit may be adjusted inwardly and outwardly within said tub, and a finishing plate extending over said container and unit and detachable therefrom, said plate being provided with openings through which said levers extend.

5. In a switch panel, a tub member, a fuse socket unit detachably mounted in the bottom of said member, said unit comprising a plurality of fuse sockets rigidly mounted on a common support, each socket having its outer end reduced, a finishing plate for forming a closure for said tub member, a guard member having openings for receiving the reduced ends of said fuse sockets whereby said guard members may be adjusted toward and from said sockets for positioning the outer ends of said sockets in said openings, and means for adjustably mounting said guard member on said plate.

6. A finishing plate for a switch box, comprising a plate provided with an opening therein, a closure for said opening, angle bars secured to the inner side of said plate and extending laterally from the edge of said opening to form a stop for said door, a tray-shaped guard member having openings in its bottom wall for receiving reduced ends of switch elements, and means for adjustably mounting said member on said bars, whereby the same

- may be adjusted toward and from said closure for positioning the reduced ends of said elements in said last-named openings.
7. In a switch panel, a switch unit comprising a pair of parallel supporting angle bars, and a plurality of switch elements secured to one of the flanges of each of said bars transversely thereof, the other flanges of said bars being provided with parallel slots 10 opening in the opposite direction from said elements.
8. In a switch panel, a tub member, a cross-bar extending across said member adjacent one wall thereof, supporting members 15 on said wall and bar, a switch unit supported on said supporting members, said unit comprising a plurality of switch elements each having a switch lever, a finishing plate detachably secured over said tub member for enclosing said unit and having openings 20 through which said levers extend, and means for adjustably connecting said supporting members to said wall and bar whereby the same may be adjusted transversely of said 25 supporting members.
9. In a switch panel, a tub member, a cross-bar extending across said member adjacent one side wall thereof, supporting members 30 on said wall and bar, a switch unit supported on said supporting members, said unit comprising a plurality of switch elements each having a switch lever, a finishing plate on 35 said unit and tub member having openings for receiving said levers, and screws extending through said finishing plate and threaded into said unit for adjusting the same to position said levers relative to said plate.
10. In a panel box of the class described a circuit control device fixed upon the bottom 40 of the box, a cover for the box, an opening in the cover opposite the control device, a partitioning member extending from the circumference of the opening in the cover to the top of the control device, and means for 45 telescopically mounting the partitioning member on the cover to provide for variations in the distance between the cover and the control device.
11. In a panel box of the class described, a 50 circuit control device fixed upon the bottom of the box, a cover for the box, an opening in the cover opposite the control device, partitioning means extending from the circumference of the opening in the cover to the top 55 of the control device, the partitioning means including relatively slidabile members whereby provision is made for variations in the distance between the cover and the control device.
12. In a panel box of the class described, a 60 circuit control device fixed upon the bottom of the box, a cover for the box, an opening in the cover opposite the control device, partitioning means extending from the circumference of the opening in the cover to the top 65 of the control device, the partitioning means including a supporting member rigidly fixed to the cover, and a second member movably attached to the supporting member, and means to guide the second member in its 70 movement.
13. In a panel box of the class described, a circuit control device fixed upon the bottom of the box, a cover for the box, an opening in the cover opposite the control device, partitioning means extending from the circumference of the opening in the cover to the top 75 of the control device, the partitioning means including a supporting member rigidly fixed to the cover, and a second member movably attached to the supporting member, and means to guide the second member in its 80 movement, the last mentioned means comprising elongated formations in the movable member, and means on the supporting member to cooperate therewith.
14. In a switch panel, a tub member, a finishing plate for constituting a closure for said tub member, said plate having openings 85 therein, a partition within said member, a switch unit within said member between the partition and a wall of said tub member, said unit comprising a pair of supporting bars, and a plurality of switch elements secured to said bars, each of said elements having operating levers extending through said openings, each of said bars having slots extending transversely to said finishing plate, and means secured to said wall and partition for 90 engaging said slots for holding said unit in adjusted position within said tub, whereby when said tub is placed in position in a partition wall the outer face of said unit may be adjusted to the plane of the plastering on said wall for receiving said finishing plate.
- In testimony whereof I affix my signature. 95
